FUEL INJECTOR

Louis O. French, Milwaukee, Wis.

Application August 28, 1948, Serial No. 46,683

1 Claim. (Cl. 103—41)

1

The invention relates to fuel injectors and more particularly to those in which the pump and the nozzle are formed as a unit.

One of the objects of this invention is to provide a unit injector in which any products of combustion are effectively prevented from blowing back into the pump chamber.

A further object of the invention is to provide an automatic or compression pressure operated unit fuel injector in which the operating piston is effectively sealed against the escape of gases from the combustion chamber.

A further object of the invention is to provide an automatic or compression pressure operated unit fuel injector in which the operating piston is efficiently cooled by a continuous circulation of fuel while fuel is intermittently supplied from the same fuel supply as a checking fluid to vary the stroke of the operating piston.

A further object of the invention is to provide a novel arrangement of pump discharge valve, injection pressure control valve, and fuel discharge conduit for fuel injectors.

A further object of the invention is to provide an injection pressure control valve of the differential needle type of simple and compact construction.

The invention further consists in the several features hereinafter described and more particularly defined by claim at the conclusion hereof.

In the drawings:

Fig. 1 is a vertical sectional view through a fuel injector embodying the invention;

Fig. 2 is a vertical sectional view taken on the line 2—2 of Fig. 1;

Fig. 3 is a horizontal sectional view taken on the line 3—3 of Fig. 1;

Fig. 4 is a side elevation view of a portion of the operating piston;

Fig. 5 is an enlarged sectional view of the check valve and the injection pressure control valve showing certain modifications.

Referring to the drawings, the injector has the relatively fixed metal housing parts comprising a piston stop 6, cylinder 7, and cap 8.

The stop 6 is a ring seating on an annular flange 9 formed in the head 10 of an internal combustion engine and has a valve seat surface 11.

The cylinder 7 has a flat top and a straight bore 12, a counter bore 13, a relief port 14, a coolant supply port 15, and a coolant return port 16. In the form shown, the fuel is used as the coolant. The cylinder 7 is secured in the en-

2

gine head against the stop 6 by any suitable clamping means.

The cap 8 has a flat faced flanged end 17, a guide bore 18, and a valve seat 19 at the inner end of said bore. It also has a checking fluid inlet 20 in which a spring closed check valve 21 is mounted. A packing ring 22 of elastic material, such as a suitable synthetic rubber composition, is mounted in the counterbore 13 and compressed between the cylinder 7 and the cap 8 when the flat faces of said cap and cylinder are clamped together by screw bolts 23 passing through the flanged portion of the cap and anchored in the cylinder.

A piston 24 working in the bore 12 is moved in one direction by the compression pressure of the gases in the combustion chamber C of the engine and in the opposite direction by a spring 25. The piston 24 has an operating piston portion 26 and a checking piston portion 27 and a high pressure pump bore 28 provided with fuel inlet ports 29.

The portion 26 is provided with a groove 30 to receive an O-ring 31 of elastic material, such as a suitable synthetic rubber composition, and with a recess 31 to receive abutting metal piston rings 32 which are retained therein by sleeve nut 33 mounted on the reduced threaded end 34 of said piston and provided with wrench engaging flats 35. Portion 26 also has a bore 36 of larger diameter than the bore 28 and forming a shoulder 37, and it is also preferably annularly recessed at 38 back of the ring portion 30 to increase the cooling surface adjacent said ring. The piston 24 is preferably a casting, and where the pump bore 28 is integral, it may be made of a suitable alloy steel. Where said piston 24 is made of cast iron or aluminum, it may have the usual hardened steel liner for the bore 28.

A check valve interposed between the high pressure pump chamber 39 and the injection pressure control valve is formed by a metal ring member 40 provided with an internal flange 41 forming a seat for one side of a valve member in the form of an O-ring 42 of elastic material, such as a suitable synthetic rubber composition. A metal ball valve 43 is mounted in the ring 40 and seats on the other side of the O-ring 42 and is held thereagainst under a predetermined compression due to the spacing of the bottom plate 44 from the flange 41, said plate having a central fuel passage 46 connected by grooves 47 in the top face of its projection 48 with the interior of the sleeve or ring 40. Fuel from the pump chamber is forced outwardly from the pump

chamber against the inner bore of the elastic ring 42 which will yield enough so as to allow the fuel to pass between said ring 42 and the ball 43. Should gases from the engine reach this valve, they will act on the ball 43 tending to exert further pressure on the ring 42 than that initially imposed and acting to hold said ring 42 in sealing engagement with the ball and in sealing engagement with the flange 41. The gases may also act upon the lower exposed surface of the ring 42 tending to hold it against the seat formed by the flange 41. No seat grinding is necessary for this check valve structure, and the O-ring 42 forms in effect a closing spring.

A fuel discharge passage member 49 is provided with differential bores 50 and 51 in which a differential needle valve 52 is mounted, said valve seating on a seat 53 at the end of the bore 51 which may at this end form with the valve a spray nozzle 54, as shown in Fig. 1, or which may be connected by a passage 55 with a spray orifice or nozzle 56, as shown in Fig. 5. Valve 52 has a flange portion 57 of large diameter and a stem portion 58 of reduced diameter, the differences in area between these portions being greater than the area of the said stem and its prolongation 59 on the other side of said flange 57. A fuel passage 60 extends through the portions 58 and 57 and into the prolongation 59 and connects below the flange portion 57 with a cross-passage 61 communicating with the lower end of the bore 50. The annular space between the stem portion 58 and the bore 50 is filled with an elastic packing, conveniently formed by a stack of O-rings 62 of a suitable synthetic rubber composition. With the valve in assembled position the plate 44 in abutting the top of member 49 puts a predetermined pressure on the rings 62 which in turn act to hold the valve 52 against its seat. When the pressure in the high pressure pump builds up to a point above that of the initial pressure imposed on the packing or rings, the fuel passing through the passages 60 and 61 acts on the lower face of the valve 52 and lifts the same from its seat and fuel may then pass through the discharge member 49 to the spray nozzle. It will be noted that the fuel passing through the stem cools those portions of the valve with which the O-rings 62 are in contact. The stem portion 58 preferably extends above the top of the packing to facilitate disassembly, and the lift of the valve 52 may be limited by the top of said stem engaging the top of the guide bore 63 in the plate 44. The prolongation 59 is provided with flats 64 to form fuel passages to the lower end of the bore 51.

The member 49 may have direct threaded connection with the lower threaded end of the nut 33, or it may be mounted in the differential bores 65 and 66 of a sleeve nut 67 provided with wrench engaging flats 68 and with a conical seating surface 69 which normally seats on the seat surface 17. The nut 67 clamps both of the valve assemblies in the lower end of the operating piston.

A high pressure pump plunger 70, working in the bore 28, controls the ports 29, and after their closure on the outward movement of piston 24, fuel is compressed or put under pressure in the pump chamber 39 until the closing pressures of the check valve and the needle valve are overcome, and then this fuel is discharged into the combustion chamber through the spray orifice, the amount of fuel depending upon the relative movement of said plunger and piston 24. To

vary this amount, the effective stroke of piston 24 is varied by checking more or less of the checking fluid in the upper part of the cylinder 7 or in the chamber 71 to stop the movement of said piston. For this purpose the part 27 is provided with a triangular notch providing control edges 72 and 73 which cooperate with the port 14 to cut off said port sooner or later as said piston 24 is moved outwardly, the particular part of the available stroke period at which this occurs being determined by the angular setting of said edges 72 and 73 relative to said port so as to produce either a complete lapping of this port relative to the control edge 72 or a lapping 15 of said port after a predetermined movement of said piston.

For adjusting the angular position of control edges 72 and 73 relative to the port 14, a rotatable valve like member 74 mounted in the bore 18 and seating on the seat 19 has depending key projections 75 slidably engaging in key slots 76 in a flange 77 at the top of the piston part 27. The exposed end of the stem of the member 74 has an operating handle 78 slidably keyed there-to and secured by a nut 79 against a shoulder on said stem. The spring 25 engages the head of plunger 76 which in turn abuts the head of member 74, so that the same is normally sealed against the cap 8. By rotation of the member 74 either 25 through the handle 78 or any other suitable turning means, such for example, as a rack and pinion, the piston 24 is moved to the desired position relative to the port 14.

The loading of spring 25 may be used to determine the time of injection, but preferably the timing of the injection is controlled by a variable pressure relief valve comprising a valve casing 80, a valve 81, and an adjustable closing spring 82 associated with the relief port 14. The valve 81 carries an elastic O-ring 81'.

The casing 80 has a passage 83 connecting port 14 with a valve seat 84 and a guide bore 85 enlarged adjacent the seat and connected by a return passage with piping leading back to the fuel supply pump. Casing 80 has a threaded end 86 for a manually adjustable spring tensioning nut 87. The loading of the spring 82 acting to close the valve is sufficient to check the movement of the piston 24 until the desired time for injection, near the end of the compression stroke, has been reached, and this time may be varied to suit engine operating conditions.

The fuel supply piping has been indicated diagrammatically in Figs. 1 and 3 wherein the numeral 88 designates a fuel supply pipe for connection with any suitable low pressure fuel pump and provided with branch connections 89 and 90 connecting, respectively, with the check valve 21 and the inlet port 15. A fuel return pipe 91 leading back to the supply tank, respectively, connects by branch connections 92 and 93 with the return port 16 and the outlet from the timing relief valve. Thus the fuel is continuously circulated through the space 94 in the bore 12, cooling the piston 24 and supplying the high pressure pump chamber 39 with fuel while the chamber 71 is supplied with fuel as a checking fluid in accordance with its requirements, the displaced checking fluid returning to the fuel supply. The fuel supply system will, of course, have a suitable cooler so that the piston 24 is kept at a temperature low enough to prevent deterioration of the elastic ring members previously referred to, and such cooling may be aided by the usual water cooling of the engine.

With the above construction, the lower end of the piston 24 being exposed to the pressure of the gases in the combustion chamber C of the engine, when this pressure exceeds the loading of spring 25 and the spring 82, port 14 is opened to relief and piston 24 moves outwardly, closing off the ports 29 and building up pressure in the pump chamber 39 which then acts to open the check valve including ring 42 and to open the needle valve 47 to cause the injection of fuel. The unit pressure imposed on the checking fluid in chamber 71 to hold the operating piston against movement is relatively low compared to the fuel injection pressure. Angular adjustment of piston 24 changes the amount of fuel injected, and adjustment of the relief valve changes the time of injection.

Reference is here made to my copending applications Serial No. 748,140, filed May 14, 1947, for "Fuel Injector," and Serial No. 785,179, filed November 10, 1947, as to claims for common subject matter.

I desire it to be understood that this invention is not to be limited to any particular form or arrangement of parts except in so far as such limitations are included in the claim.

What I claim as my invention is:

In a fuel injector, the combination of a housing provided with a bore and fuel inlet and discharge passages and a relief passage communicating with said bore, said housing also provided with a check valve controlled checking fluid inlet passage communicating with said bore, a fuel supply pipe connected with said fuel inlet passage and the checking fluid inlet passage, a return pipe connected with said fuel discharge passage and said relief passage, a piston movable in said

bore in response to gases under compression having an operating piston portion and a checking piston portion spaced therefrom to form a cooling space, said fuel inlet and discharge passages being in continuous communication with said space in any position of said piston in said cylinder for continuously circulating fuel through said space, a fuel pump having its bore in said piston, a pump plunger held against longitudinal movement and working in said fuel pump bore to discharge fuel therefrom on the movement of said piston by said gases, means for supplying fuel to said fuel pump, said checking piston portion having a control edge cooperating with said relief port to vary the amount of checking fluid discharged through said relief port to variably limit the movement of said piston and thereby vary the amount of fuel delivered by said fuel pump, and means for angularly adjusting said piston relative to said relief port.
